US00D516484S

(12) **United States Design Patent** (10) Patent No.: **US D516,484 S**
Koch (45) Date of Patent: **** Mar. 7, 2006**

(54) **TIRE RIM**

(75) Inventor: **Adolf Koch**, Waiblingen (DE)

(73) Assignee: **Sport-Service Lorinser Sportliche Autoausrüstung GmbH**, Waiblingen (DE)

(**) Term: **14 Years**

(21) Appl. No.: **29/160,738**

(22) Filed: **May 15, 2002**

(30) **Foreign Application Priority Data**

Nov. 22, 2001 (DE) 4 01 10 129

(51) **LOC (8) Cl.** **12-16**

(52) **U.S. Cl.** **D12/209**

(58) **Field of Classification Search** D12/204-211; 301/37.101, 64.101, 65

See application file for complete search history.
